WELT HOOK FOR KNITTING MACHINES

Kenneth Howie, Norristown, Pa., assignor to
Wildman Mfg. Co., Norristown, Pa., a corpora-
tion of Pennsylvania

Application September 28, 1939, Serial No. 296,992

4 Claims. (Cl. 66—96)

The invention relates to welt hooks for turning welt on a full fashioned knitting machine.

One object of the invention is to provide a welt hook, the point of which will be shielded against contact with the stitch when this is pushed down onto the needle from the welt implement onto the knitting needle.

In the accompanying drawing

Figure 1 is a view of the improved welt implement looking at it from the front thereof, i. e., at the face on which the hook is located.

Fig. 2 is a side view of the improved implement.

Fig. 2a is a cross section of the implement on the line 2a—2a of Fig. 2.

Fig. 2b is a cross section on the line 2b—2b of Fig. 2.

Fig. 2c is an enlarged view of the hook of Fig. 1 and the adjacent part of the stem of the welt implement.

Fig. 3 is a diagrammatic view of the improved welt implement in position relative to the knitting needle with the upper layer or section of the welt fabric ready to be pushed down onto the knitting needle.

Fig. 4 is a diagrammatic view similar to Fig. 3 with the upper layer of the welt fabric pushed down onto the stem of the needle below the beard thereof adjacent the under layer of the welt ready to proceed with the knitting of the leg fabric.

Fig. 5 is a modification showing that the stem, near the hook, instead of tapering to the nose of the welt implement, may be otherwise reduced in width below the plane where said stem shields the point of the hook.

The improved welt hooks are mounted in a row in a transfer bar (not shown) as in ordinary practice to receive the loops of the first course of knitting, and to hold the same while the desired length of fabric is knit for turning the welt. This implement has a stem or main body 1 provided with a butt 2 by which the implement is mounted in the ordinary transfer bar.

It is provided with an eye 3 on its front face, i. e., the same face on which the hook 4 is located. The point of this hook, instead of being widely separated from the stem of the implement, is separated from the face of the stem by only a slight space, as indicated at 5 in Fig. 2. In other words, the point of the hook is made to lie as close as possible to the face of the underlying stem, consistent with its capacity to receive the yarn therein, which, in fine gauge machines, is very close.

The stem at 6 is of less width than the width of the main body of the implement which contains the eye 3, but on the other hand, this portion 6 of the stem just above the hook is of considerably greater width, comparatively speaking, than the width of the hook itself, and this is particularly so of that portion which lies adjacent the hook where it is tapered in width to form the point.

In other words, the point of the hook lying in the longitudinal center plane of the stem 6 of the implement is spaced apart a substantial distance, comparatively speaking, from the adjacent side faces of the stem portion 6, so that the point of the hook lying close to the face of the wider stem portion 6 is shielded by this comparatively wide stem portion from contact with the loop on the implement. Therefore, as the loop a, Fig. 3, is pushed downwardly along the hook end of the implement, it will not be caught by the hook, but, on the contrary, it will move freely past the hook from the position shown in Fig. 3 to the position shown in Fig. 4, lodging on the stem of the spring beard needle below the beard thereof in which position it is entirely free from the welt hook, and is completely positioned on the needle stem in such relation to the beard that when the operation of knitting is proceeded with, involving the pressing of said beard, it will be cast off together with the loop a¹ of the lower layer of the welt and become a part of the fabric.

The wide part of the stem 6 of the implement extends to a point near a transverse plane at about the middle of the length of the hook, as viewed in Fig. 1. From this point, indicated at T, the width of the stem underlying the hook tapers to the nose of the implement at 7. At this end, the implement is small in width.

It will be noted from Figs. 3 and 4 that in the loop transfer operation, the hook of the welt turning implement lies against the back of the needle, where it is additionally shielded by the stem of the needle from catching the yarn. Although the welt turning implement of the invention is illustrated in these figures in association with a knitting needle having an eye in the side thereof opposite from the beard side for receiving the hook of the implement, the invention is not limited in this respect, as the shielding function which is an object of the invention is obtained if the implement is used in a machine having needles which do not have a hook receiving eye.

For convenience of description, the end of the

implement where the stem merges into the hook may be termed the "nose" of said implement, or the "bend" of the hook.

Fig. 2 shows that the inner face of the hook which lies close to the stem of the implement is substantially parallel with the opposing face of said stem. The hook is sufficiently rigid to permanently maintain this relationship, since this implement is not of the yielding or spring beard type.

The welt bar may be connected up in the knitting machine under tension in the usual manner, after being operated by hand.

The invention is not limited to a hand operated welt bar, because the improved transfer hook may be employed in an automatic machine without departing from the scope of the invention.

The invention is not limited to the tapered form of the stem of the needle between the zone T and the point where it merges into the base of the hook. For instance, the end of the stem adjacent the hook can be of the form shown in the enlarged view Fig. 5, in which form from the zone, which corresponds substantially to the zone T of Fig. 1, the end of the stem is abruptly reduced in width, instead of being reduced by a gradus' taper. This abrupt reduction in width, however, is so located that the point of the hook is still shielded by the wide portion of the stem. In other words, the abrupt reduction in width of the stem begins at a level well below the level of the point of the hook so that said point will be shielded by the wide stem adjacent said point.

I claim:

1. A welt turning implement comprising a stem portion and a rigid returned portion lying in a fixed position approximately parallel to but spaced from the stem portion to form a permanently open hook, said stem portion having an eye therein on the same side thereof with the returned portion and located along the stem spaced from the returned portion to receive the end of a knitting needle, said returned portion having a pointed end, and said stem portion increasing in width away from the end of the implement where the returned portion merges into

the stem portion so that the stem portion is wider at its part underlying said pointed end than any part of the returned portion.

2. A welt turning implement comprising a stem portion and a rigid returned portion lying in a fixed position parallel to but spaced from the stem portion to form a permanently open hook, the end of said returned portion being pointed, the point lying in the longitudinal center plane of the stem portion, and the part of said stem portion which is adjacent to the pointed part of the returned portion being wider than any part of the returned portion whereby the point of the implement will be shielded against catching in the yarn of a loop, and also being wider than the end where the returned portion merges in the stem.

3. A welt turning implement comprising a stem portion and a rigid returned portion lying in a fixed position spaced from the stem portion to form a permanently open hook, the end of said returned portion being pointed, and the part of said stem portion which is adjacent to the pointed part of the returned portion being wider than any part of the returned portion whereby the point of the implement will be shielded against catching in the yarn of a loop, the part of the stem portion adjacent to the unpointed part of the returned portion being no wider than this unpointed part of the returned portion.

4. A welt turning implement comprising a stem portion and a rigid returned portion lying in a fixed position spaced from the stem portion to form a permanently open hook, the end of said returned portion being pointed, and the part of said stem portion which is adjacent to the pointed part of the returned portion being wider than any part of the returned portion whereby the point of the implement will be shielded against catching in the yarn of a loop, the part of the stem portion adjacent to the unpointed part of the returned portion tapering gradually from the widened part of the stem portion to the end of the implement where the returned portion merges into the stem portion.

KENNETH HOWIE.
